APPARATUS FOR OPERATING ELECTRIC
DISCHARGE DEVICES

John H. Campbell, Painesville, and Delmar D. Kershaw, Cleveland, Ohio, assignors to General Electric Company, a corporation of New York

Application December 8, 1951, Serial No. 260,694

7 Claims. (Cl. 315—187)

1

This invention relates to apparatus for starting and controlling gaseous electric discharge devices such as fluorescent lamps, and more particularly to circuits suitable for instant start lamps, that is, lamps wherein the discharge is initiated by the application of an instantaneous high voltage and wherein the electrodes are not preheated at starting.

The invention is concerned with a starting and operating apparatus of the type commonly known as a sequence-start series ballast wherein two lamps are operated in series after starting in sequence. Such apparatus generally comprises a transformer or auto-transformer having a primary winding and a high leakage reactance secondary winding, both windings having a current carrying capacity at least sufficient for the normal operating current of the lamps. In addition, there is provided some means, such as an auxiliary winding of relatively low current carrying capacity, which is connected to assist in starting the lamps. After one lamp has been started, the reduced voltage drop across it permits starting of the second lamp without difficulty.

With the present sequence-start series type of ballast, the difficulty has been encountered that the auxiliary winding, when it is designed to have a current carrying capacity sufficient for its starting function only, often burns out when one of the lamps approaches the end of its life. Such burning out appears to be due to the fact that one of the cathodes in a lamp generally becomes deactivated before the other. When this condition prevails, the lamp tends to operate as a half-wave rectifier, resulting in a flow of unidirectional current through the auxiliary winding with consequent saturation of its core, reduction of its reactance, and increase in current. In order to avoid overheating under these conditions, it has been found necessary to construct the auxiliary winding with a much higher current carrying capacity than is necessary for its normal function.

An object of the present invention is to provide a new and improved sequence-start series type ballast for discharge devices which avoids the above-described difficulties.

Another object of the invention is to provide improved sequence-start series circuits for discharge lamps which lend themselves particularly well to disconnecting the primary winding from the supply circuit by the removal of either lamp from its connectors or lampholders.

In accordance with our invention, the operat-

2

ing circuit comprises a high leakage reactance transformer whose main function is to provide operating voltage and at the same time to regulate the current in a pair of series connected lamps. In addition, there is provided in the transformer an auxiliary or extended winding of relatively low current carrying capacity. The current capacity of this winding need be merely equal to the current required to establish hot spots on the electrodes of the lamps in order to reduce the voltage drop across the arc discharge to a value close to the operating value. In view of its extremely low current capacity, the auxiliary winding adds comparatively little to the cost of manufacture of the transformer, and, when connected in accordance with our improved circuit, it permits a very considerable reduction in the open circuit voltage required of the secondary winding. The secondary winding naturally must have a comparatively large current carrying capacity, at least sufficient to provide the rated current to the lamps, so that it is economically advantageous to add the auxiliary winding in view of the reduction in size of the main winding which it permits.

For further objects and advantages and for a better understanding of our invention, attention is now directed to the following description and to the accompanying drawings. The features of our invention believed to be novel will be more particularly pointed out in the appended claims.

In the drawings, wherein like reference numerals denote corresponding elements:

Fig. 1a is a schematic diagram of the basic circuit of our invention and Figs. 1b to 1d are vector diagrams relating thereto.

Figs. 2a and 3a are schematic diagrams of modified circuits embodying our invention wherein provision is made for disconnecting the primary winding when either lamp is removed from its socket. Figs. 2b to 2d and Figs. 3b to 3d are the corresponding vector diagrams.

Referring to Fig. 1a, there is shown a pair of long tubular electric discharge devices D1 and D2, which may for example be 75 watt fluorescent lamps 3 feet in length and 1½ inches in diameter. Each lamp is provided with a pair of activated filamentary electrodes 1, 1' enclosed in elongated envelopes containing mercury vapor at a low pressure and a suitable starting gas such as argon. The lead-in wires of each electrode are short circuited together and brought out to respective single contact pins 2, 2', as is the case with the commercial 75 watt fluorescent lamps

known as 96-T-12. These lamps require approximately 565 volts between their electrodes for starting, and during normal operation may draw 425 milliamperes with a voltage drop of approximately 190 volts between the electrodes.

The lamps D1 and D2 are started and operated by means of an auto-transformer 3 comprising a primary winding P, a secondary winding S, and an auxiliary winding A. The primary winding P is adapted to be energized at terminals 4, 5 from a source of alternating current supply, which may for example be the usual 118 volt 60 cycle lighting circuit.

The main operating circuit for lamps D1 and D2 comprises primary winding P, secondary winding S, a ballasting capacitor C1, and the lamps D1 and D2 all connected in series. The secondary winding S has a high leakage reactance, which characteristic may be achieved by the use of the usual magnetic shunt in the core structure as indicated diagrammatically at 6. The primary and secondary windings are connected in aiding voltage relationship, as indicated by the arrows e_p and e_s , and the sum of their open circuit voltages generated between terminal 4 and junction point 7 may be slightly in excess of the voltage required to start a single one of the lamps, for instance 580 volts. It will be understood that the voltage required to start a single one of the lamps is more than sufficient for the operation and regulation of the two lamps in series after the discharges have been initiated. Due to the presence of capacitor C1, the lamps draw leading current from the operating circuit. However, by reason of the additional lagging current drawn by the primary winding for magnetizing the core structure, the transformer as a whole draws substantially unity power factor current from the lighting circuit at terminals 4, 5.

The low current capacity auxiliary winding A is connected between terminal 4 of primary winding P and a junction point 8, which point is connected through a coupling capacitor C2 with the junction point 9 between lamps D1 and D2. The auxiliary winding may be either tightly or loosely coupled to the primary winding: if it is tightly coupled, capacitor C2 may be of lower voltage rating but must have a slightly higher capacitance value than need be the case if the auxiliary winding is loosely coupled. In this particular example of the invention, the auxiliary winding is loosely coupled, the magnetic shunt being indicated diagrammatically at 10. The auxiliary winding is connected in aiding voltage relationship with the primary and the secondary within the starting loop for lamp D1, as indicated by the arrow e_a . The starting loop comprises all three windings in series and is completed through capacitor C1, lamp D1, and capacitor C2. By reason of the presence of the two capacitors C1 and C2, and especially by reason of capacitor C2 which is of small value and has a high reactance, the starting loop draws leading current to start lamp D1. A small value is purposely chosen for capacitor C2, since it need pass only the current necessary to initiate the formation of hot spots on the electrodes 1, 1' of lamp D1. For commercial fluorescent lamps provided with filamentary activated electrodes, a minimum current of 100 milliamperes is generally regarded as satisfactory for initiating hot spots on the electrodes.

In operation, assuming that the normal supply voltage is applied to the input terminals 4, 5

of primary winding P, the sum of the primary and secondary open circuit voltages e_p and e_s is not, of itself, sufficient to cause the striking of an arc within the two lamps in series. However, the voltage e_a developed in the auxiliary winding, when added to the primary and secondary voltages, results in a voltage which is more than sufficient to strike an arc within lamp D1. The open circuit voltage across lamp D1 is represented by the broken line V_{D1} in the vector diagram of Fig. 1b.

Hot spots are formed practically instantaneously on the electrodes of lamp D1, so that the voltage drop across it decreases nearly to its normal operating value, as indicated by vector V_{D1} in Fig. 1c. By reason of the inclusion of capacitor C2 in the starting loop including the three windings in series, the current flowing at this time is substantially of leading power factor, as indicated by the vector I. As is well known, the circulation of a leading current through a high leakage reactance winding produces a voltage drop which is in phase to add to the voltage induced in the winding by transformer action. Thus, after lamp D1 had started but before lamp D2 has struck, the voltage between terminal points 4 and 7 is actually greater than the sum of the open circuit voltages of the primary and secondary windings. These conditions are indicated by the lengthening of the vectors e_s and e_a in Fig. 1c, and also by their slight retardation in phase occasioned by the fact that the current drawn by lamp D1 leads the induced voltage by slightly less than a full 90°. The increase in the voltage vector e_s compensates to a certain extent for the voltage drop V_{C1} across capacitor C1. Moreover the voltage drop across lamp D1, by reason of the fact that it is almost at right angles to the induced voltages e_p and e_s , causes at the worst but a very slight reduction and may even cause an increase in the voltage appearing between junction points 9 and 4. This voltage, indicated by the dotted vector V_{D2} in Fig. 1c, is that which is effective in starting lamp D2. As a result, lamp D2 strikes and the discharge current increases to its normal value, generally in the neighborhood of 400 milliamperes for the commercial fluorescent lamps described. The conditions then are indicated by the vector diagram of Fig. 1d and the regulation of the discharge current is established by the excess in capacitive reactance of capacitor C1 over the inductive leakage reactance of secondary winding S.

The successive operations which have been described, all take place within a very short interval of time amounting to a fraction of a second only. Thus, although the lamps start in sequence, the delay between them in starting is so brief that, to a casual observer, they appear to start simultaneously. The vector relations during normal operation of the lamps is indicated in Fig. 1d and it will be observed that the voltage produced by the auxiliary winding and indicated by vector e_a is largely cancelled by the voltage drop V_{C2} across the high impedance of capacitor C2. Moreover these voltages are in such phase that they have but a very slight tendency to unbalance the currents circulating in the two lamps, in consequence of which the lamps light up with substantially equal brillance.

It will be observed that the inclusion of capacitor C1 in the main operating circuit prevents any possibility of circulation of direct current through the primary and secondary windings. Thus even though one of the electrodes of either

lamp D1 or D2 should become deactivated before the other, so that the lamp in question might tend to operate as a current rectifier, such an eventuality could only result in charging capacitor C1, and the flow of direct current could not continue. Likewise, the inclusion of capacitor C2 in the starting loop including the auxiliary winding, prevents any flow of direct current in that winding. For instance, should one of the electrodes of lamp D2 become deactivated before the other, the most adverse result would be to charge up capacitor C2 and the flow of direct current in the path comprising winding A, capacitor C2, and lamp D2 could not continue. Accordingly, winding A need be designed to have a current carrying capacity merely sufficient to initiate the formation of hot spots on the electrodes of lamp D1. This is a distinct advantage over present sequence-start circuits in which provision must be made for the increased current which occurs upon the deactivation of one electrode before the other in a lamp. Thus, through the use of an auxiliary or extended winding and a small coupling capacitor with the circuit connections which have been described, the invention provides a sequence start series ballast of smaller and more economical dimensions than heretofore possible.

In Fig. 2a, there is shown another embodiment of our invention which is a modified form of the circuit of Fig. 1a. This circuit follows the same general principles, but, by a rearrangement of parts, permits disconnecting the primary winding of the transformer from the supply lines whenever one of the lamps is removed from its socket or lamp-holder. This feature is generally referred to as a primary disconnect, and it is required by regulating authorities to eliminate shock hazard for the present type of circuit in view of the high voltages encountered.

Referring to Fig. 2a, transformer 11 corresponds in general to transformer 3 of Fig. 1 and comprises primary winding P, loosely coupled secondary winding S, and low current capacity auxiliary winding A. The auxiliary winding is tightly coupled to the primary in this example of the invention. The operating circuit for the two lamps comprises the secondary winding S between junction points 12 and 13, ballasting capacitor C1, and lamps D1 and D2 connected in series. The starting loop for lamp D1, beginning at junction point 14, includes primary winding P, auxiliary winding A, coupling capacitor C2, secondary winding S and ballasting capacitor C1. The windings are all connected in aiding voltage relationship, as may be seen by observing the direction of the voltage arrows e_p , e_a and e_s around the circuit.

The primary winding is adapted to be energized from the usual lighting circuit at terminals 15 and 16. In order to disconnect the primary winding from the line whenever either lamp is removed from its socket, terminal 16 is connected to a contact 17, which in cooperation with a second contact 18 constitutes a short-circuiting connector for contact pin 2' of lamp D1. Corresponding contacts 20 and 21 form a short-circuiting connector for contact pin 2 of lamp D2. Contact 18 of lamp D1 is directly connected to contact 21 of lamp D2, and contact 20 of lamp D2 is connected to the primary winding P at junction point 23. It will be understood that the contacts 17, 18 and 20, 21 have been diagrammatically represented and that their physical construction may correspond to either the single pin or the double pin short-circuiting lampholders or

connectors commonly used in the industry. When both lamps D1 and D2 are inserted in their connectors, the primary circuit is established from terminal 16 through the connector for lamp D1 to junction point 14, and thence through the connector for lamp D2 to junction point 23 of the primary winding. If either lamp is removed from its socket, the primary circuit is interrupted and shock hazard is thus eliminated.

When both lamps are properly engaged by their connectors, primary winding P is effectively connected between terminals 15 and 16 and furthermore a connection exists from the common junction point 14 of the lamps to terminal 23 of the primary winding. All three windings are connected in additive polarity so that their respective voltages e_s , e_p and e_a add up to produce a resultant voltage across lamp D1 sufficient to start it. This voltage is indicated by the broken line vector V_{D1} in Fig. 2b.

After lamp D1 has started, the secondary voltage e_s , the voltage drop across capacitor C2 indicated by V_{C2} and the voltage drop across lamp D1 indicated by V_{D1} , produce a resultant voltage indicated by V_{D2} in Fig. 2c, which starts lamp D2. It will be understood that the leading phase condition of the current vector I, is caused, as in the circuit of Fig. 1, by the high reactance of the coupling capacitor C2. The operating condition after the second lamp has started is shown by the vector diagram of Fig. 2d, and it is similar to that of the circuit of Fig. 1a with the difference that the operating current for the two lamps does not circulate through the primary winding.

It will be observed that the circuit connections of Fig. 2a allow for disconnecting the primary of the transformer whenever either lamp is removed from its socket. Moreover the circuit connections permit the utilization of the primary voltage to aid the auxiliary winding voltage in starting the first lamp. Thus the voltage rating of the auxiliary winding may be reduced in proportion to the additional voltage injected into the starting loop by the primary winding and some economy in copper may thereby be achieved.

An example of specific apparatus embodying our invention and constructed as described above in connection with Fig. 2a, has successfully operated a pair of 75 watt 96-T-12 fluorescent lamps requiring approximately 565 volts to start. The primary winding P operated on a supply voltage of 118 volts at 60 cycles, the secondary winding S had an open circuit voltage of 580 volts, and the auxiliary winding A had an open circuit voltage of 340 volts. Capacitors C1 and C2 had ratings of 1.7 and 0.3 microfarads respectively. The circuit started the lamps reliably even with the line voltage reduced to 95 volts. At the rated line voltage of 118 volts, the voltage drop and current for lamp D1 were 204 volts and 405 milliamperes respectively, and for lamp D2, 203 volts and 402 milliamperes respectively. Lamp D1 consumed 76.5 watts, and lamp D2 75.5 watts, and any difference in brilliance between the two lamps was practically unnoticeable to the eye.

Another embodiment of my invention is illustrated in Fig. 3a. The circuit is basically similar to that of Fig. 1, and, by a rearrangement of parts, permits disconnecting the primary winding from the line whenever one of the lamps is removed from its socket. The transformer 25 comprises primary winding P, a high reactance secondary winding S and an auxiliary winding A which is tightly coupled to the primary. The operating circuit for the two lamps comprises

secondary winding S, lamp D₁, primary winding P, lamp D₂ and ballasting capacitor C₁. The primary winding is adapted to be energized from the usual lighting circuit at terminals 26 and 27, the former being connected to junction 28 of the primary winding through short circuiting connector 29 for contact pin 2' of lamp D₂, and the latter being connected to terminal 30 through short circuiting connector 31 for contact pin 2 of lamp D₁. Thus, if either lamp is removed from its connectors or lampholders, the primary circuit is opened and the shock hazard is eliminated. It will be appreciated that the main operating circuit comprises essentially the same elements as in the circuit of Fig. 1, but that the sequence has been varied by interchanging the positions of lamp D₁ and secondary winding S in order to achieve the desired disconnect feature.

The starting loop for lamp D₁ comprises all three windings connected in series and in aiding voltage relationship, and includes coupling capacitor C₂. The starting loop may be traced, starting with electrode 1' of lamp D₁, through secondary winding S, ballasting capacitor C₁, coupling capacitor C₂, auxiliary winding A, primary winding P, and thence to electrode 1 of the same lamp.

The vector relations for the initial starting condition of the circuit are shown in Fig. 3b. The open circuit voltages of all three windings add up to produce a resultant V_{D1} which starts lamp D₁ without difficulty. After the first lamp has started, the vector relationships are as illustrated in Fig. 3c wherein the voltages e_S and e_P, together with the voltage drops V_{D1} across lamp D₁ and V_{C1} across capacitor C₁, produce the resultant V_{D2} which starts lamp D₂. The vector relationships after both lamps have started and normal operation has been achieved are illustrated in Fig. 3d.

While certain specific embodiments have been shown and described, it will of course be understood that various modifications may be made without departing from our invention. The appended claims are intended to cover any such modification coming within the true spirit and scope of the invention.

What we claim as new and desire to secure by Letters Patent of the United States is:

1. Apparatus for starting and operating a pair of gaseous discharge devices from an alternating voltage source, comprising a transformer structure having a primary winding, a high leakage reactance secondary winding, and an auxiliary winding of low current capacity, connections for energizing said primary winding from said source, a ballasting capacitor, a leading current operating circuit comprising at least said secondary winding and said ballasting capacitor and connections for including both said devices in series, a second capacitor, and a leading current starting loop comprising connections for including one only of said devices, both said capacitors, and all of said windings in series, all of said windings being connected in aiding voltage relationship within said loop.

2. Apparatus for starting and operating a pair of gaseous discharge devices from an alternating voltage source, comprising a transformer structure having a primary winding, a high leakage reactance secondary winding, and an auxiliary winding of low current capacity, connections for energizing said primary winding from said source, a ballasting capacitor, a leading current operating circuit comprising said primary and sec-

ondary windings, said ballasting capacitor and connections for including both said devices in series, said primary and secondary windings being connected in aiding voltage relationship, a second capacitor, and a leading current starting loop comprising connections for including one only of said devices, both said capacitors, and all of said windings in series, said auxiliary winding being connected in aiding voltage relationship to the other windings within said loop.

3. Apparatus for starting and operating a pair of gaseous discharge devices from an alternating voltage source, comprising a transformer structure having a primary winding, a high leakage reactance secondary winding, and an auxiliary winding of low current capacity, connections for energizing said primary winding from said source, a ballasting capacitor, a leading current operating circuit comprising said secondary winding, said ballasting capacitor and connections for including both said devices in series, a second capacitor, and a leading current starting loop comprising connections for including one only of said devices, both said capacitors, and all of said windings in series, said primary and auxiliary windings being connected in aiding voltage relationship to said secondary winding within said loop.

4. Apparatus for starting and operating a pair of gaseous discharge devices from an alternating voltage source, comprising a transformer structure having a primary winding, a high leakage reactance secondary winding and an auxiliary winding of low current capacity, connections for energizing said primary winding from said source including in series a pair of short-circuiting connectors for contacting one side of each device at a common junction point, a leading current operating circuit comprising in series said secondary winding, a ballasting capacitor and connectors for contacting the other side of each device, and a leading current starting loop comprising said primary and auxiliary windings and a coupling capacitor connected in series between one side of one device at said common point and completed through said secondary winding and said ballasting capacitor to the other side of said one device, all three windings being connected in aiding voltage relationship within said loop.

5. Apparatus for starting and operating a pair of gaseous discharge devices from an alternating voltage source comprising a transformer structure having a primary winding, a high leakage reactance secondary winding and an auxiliary winding of low current capacity, connections for energizing said primary winding from said source including in series a pair of short circuiting connectors for contacting one side of each device, a leading current operating circuit comprising in series said primary winding, one device, said secondary winding, a ballasting capacitor and the other device, and a leading current starting loop comprising said auxiliary winding and a coupling capacitor connected in series with said primary and secondary windings and said ballasting capacitor across said one device, all three windings being connected in aiding voltage relationship within said loop.

6. In combination, a pair of gaseous discharge devices, a transformer structure having a primary winding, a high leakage reactance secondary winding and an auxiliary winding of low current capacity, connections for energizing said primary winding from said source, a leading current operating circuit comprising at least said secondary

winding, a ballasting capacitor, and said devices connected in series, and a leading current starting loop comprising one only of said devices, said ballasting capacitor, a coupling capacitor, and all of said windings in series and connected in aiding voltage relationship within said loop.

7. In combination, a pair of gaseous discharge devices, a transformer structure having a primary winding, a high leakage reactance secondary winding, and an auxiliary winding of low current capacity, connections for energizing said primary winding from an alternating voltage source, a leading current operating circuit comprising said primary and secondary windings, a ballasting capacitor, and both said devices connected in series, said primary and secondary windings being connected in aiding voltage relationship, and a leading current starting loop comprising one only of said devices, said ballast-

ing capacitor, a coupling capacitor, and all of said windings connected in series, said auxiliary winding being connected in aiding voltage relationship to the other windings within said loop.
